UNITED STATES PATENT OFFICE.

PHILO R. WAGOR, OF SPRINGFIELD, MASSACHUSETTS.

DESIGN FOR A WALL TIE OR BINDER.

SPECIFICATION forming part of Design No. 31,136, dated July 4, 1899.

Application filed May 24, 1899. Serial No. 718,117. Term of patent 7 years.

To all whom it may concern:

Be it known that I, PHILO R. WAGOR, a citizen of the United States of America, and a resident of Springfield, in the county of 5 Hampden and State of Massachusetts, have invented and produced a new and original Design for a Wall Tie or Binder, of which the following is a full, clear, and exact description.

10 Reference is to be had to the accompanying drawings, in which—

Figure 1 is a plan view of the wall tie or binder of the present design. Fig. 2 is a section transversely on the line $y-y$, Fig. 1.

15 As shown in the drawings, the leading or characteristic and essential feature of my design consists in the parallel intermediate members $a-a$ of the binder, the end members $b-b$, arranged perpendicularly or at right angles to the parallel separated intermediate longitudinal members $a-a$ and which are longer than the space c between said members $a-a$, and the oppositely and outwardly inclining or divergent members $d-d-d-d$, which

unite the intermediate members $a-a$ and the 25 members $b-b$ endwise therebeyond, all of the said members or portions of the binder being in substantially the same plane.

The design, furthermore, comprises, but as a subordinate and non-essential feature 30 thereof, the rounded formations, as seen at $ffff$ —that is, at the junctions of the members $d-d$ and $b-b$ —and, furthermore, said members or portions $d-d$ merge into the intermediate parallel longitudinal members $a-a$ upon 35 the easy curves, as seen at $g-g$.

Having thus described my invention, what I claim, and desire to secure by Letters Patent, is—

The design for a wall tie or binder substantially as herein shown and described.

In testimony whereof I have signed my name in presence of two subscribing witnesses.

PHILO R. WAGOR.
